J. R. GUY.

Coupling for Railroad Train Heaters.

No. 83,488.

Patented Oct. 27, 1868.

United States Patent Office.

JOHN R. GUY, OF SPRINGFIELD, OHIO, ASSIGNOR TO RICE AND GUY, OF SAME PLACE.

Letters Patent No. 83,488, dated October 27, 1868.

IMPROVEMENT IN COUPLINGS FOR RAILROAD-TRAIN HEATERS

The Schedule referred to in these Letters Patent and making part of the same.

To all whom it may concern:

Be it known that I, JOHN R. GUY, of Springfield, in the county of Clark, and State of Ohio, have invented a new and useful Improvement in Apparatus for Heating Railroad-Cars; and I do hereby declare that the following is a full, clear, and exact description of the same, reference being had to the annexed drawings, making part of this specification, in which—

Figure 1 is a perspective view of the furnace;

Figure 2 is a vertical section of the same; and

Figure 3 is a side elevation, partly in section, of the pipe for connecting the cars.

The same letters are employed to designate the same parts in the different figures.

In the annexed drawings, A is the exterior casing, within which is a furnace, B, of ordinary construction, for wood or coal. The draught from the furnace passes through the pipe C.

D is the hot-air chamber between the furnace and the casing A. In this chamber is placed a fan, E, or other equivalent machine, for forcing the air through the pipe E¹ from the hot-air chamber into the other cars in the train. This furnace is intended to be placed in the baggage-car, and the heated air is driven therefrom through pipes connected through the train, with registers in each car for regulating the admission of the heated air.

The fan is driven by a belt, F, passing over the pulley E² and over another pulley placed on an axle of the car.

In order that the pipes may be connected from car to car, it is necessary that a coupling-pipe shall be used, which will permit the usual longitudinal vertical and lateral motion of the cars, and at the same time one which may be easily attached or detached. This I accomplish by the coupling shown in fig. 3, in which G is the pipe, permanently attached to the car. On the ends of this pipe I place sockets, H, the mouths of which are made flaring, as shown in the sectional part of fig. 3.

I is the coupling-pipe, on each end of which is a ball fitting accurately into the socket H. The socket being made of iron, this ball should be made of some softer metal, such as copper. An elastic packing may be used on the ball, as indicated in the section, if preferred. I do not, however, regard this as essential. This ball-and-socket joint will accommodate every movement of the cars. The length of the sockets will permit the necessary longitudinal play, and as the ball will draw out of the socket when the cars are disconnected, and may be guided into it on coupling the cars, it will be seen that it presents no inconvenience in coupling or uncoupling the cars. This tubular coupling may be used for heating the cars with either hot air or steam, or for transmitting gas for illuminating the cars.

Two of these furnaces may be used, connected either with separate sets of pipes, or, by a branch-pipe, with one set, to be employed alternately as the car is running in opposite directions.

The furnace-door should be locked, and wire gauze or perforated plates attached to the draught exit to prevent the escape of coals in case of the overturning of the car.

The fan may be used to force cold air through the cars for ventilation in warm weather.

What I claim as my invention, and desire to secure by Letters Patent, is—

In combination with the permanent pipes G and elongated, open sockets H, constructed with flaring mouths, the tubular coupling formed by a single rigid pipe, I, terminating with balls I', fitting said sockets, substantially as and for the purpose set forth.

In testimony whereof, I have signed my name to this specification in the presence of two subscribing witnesses.

JOHN R. GUY.
